APPARATUS FOR CLEANING OF
FLUE GASES

Tom Conrad Biéth, Goteborg, Sweden

Application November 7, 1944, Serial No. 562,302
In Sweden December 18, 1939

4 Claims. (Cl. 183—34)

1

The present invention relates to a new arrangement or apparatus for separating and removing dust from the flue gases being discharged through chimneys. The principal object of the invention is to provide a concentrator for intensifying a dust film along the inner walls of a chimney which when used in combination with a dust collector will more efficiently separate the dust or heavier solid particles from the flue gases and thereby permit a larger quantity of the gases to be exhausted through the chimney.

Other objects of the invention will be in part obvious and in part hereinafter pointed out as the description continues.

In the drawing:

Fig. 1 is a vertical sectional view of a chimney having my invention applied thereto with the dust collector and circulating fan shown in side elevation.

Fig. 2 is a top plan view.

In the drawing 1 indicates a conventional sheet metal chimney the upper end of which terminates in an outwardly flared collar 2. Retained in spaced relation above the collar 2 of the chimney is a cylindrical casing 3 having an inwardly flared collar 4 formed at the lower end thereof and these collars 2 and 4 being so spaced apart as to form annular opening or space 5 therebetween. Secured to the casing 3 is a ringshaped disc 6 and a corresponding disc 7 is secured to the chimney 1 and these discs are connected together by means of a cylindrical wall 16 forming a channelway 8 which communicates with the opening 5. Extending tangentially from this channelway 8 is a duct 9 leading to a dust collector 10. Leading from the dust collector is a pipe 11 and this pipe 11 is connected to the suction side of a fan 12. A pipe 13 leads from the exhaust side of the fan 12 and is in communication with an opening 14 formed within the chimney 1 and this latter opening is arranged tangentially with relation to the inner circumference of the chimney. Supported centrally within the chimney is an elongated closed body or deflector 17 having its larger lower end position above the opening 14 and its upper end tapering to a point located adjacent the upper end of the chimney.

From the foregoing it is obvious that when my improved apparatus is applied to a conventional chimney and the dust collector and fan set in motion, gases will be caused to enter the chimney through the opening 14 and caused with aid of the elongated body 17 to be set up into a centrifugal motion whereby the heavier solid particles of dust will be thrown out against the inner

2

circumference of the chimney and be caused to be drawn upwardly through the latter with the smoke and gases arising through the chimney. This intensified dust film will escape through the annular opening 5 into the channelway 8 where it will be drawn within the dust collector 10. The dust film will be caused to circulate within the channelway 8 in the direction of the arrows as shown in Fig. 2 of the drawing and then caused to pass through the duct 9 into the dust separator where the dust film is thoroughly cleaned. The cleaned gas will escape through the pipe 11 into the fan 12 where it will be again forced through the pipe 13 into the chimney. From this arrangement it will be apparent that the solid particles contained within the gas film will be thoroughly separated therefrom and be prevented from exhausting from the chimney which would likely cause a hazard to surrounding buildings or 20 persons.

Whereas in the drawing I have disclosed a single dust collector and fan, any number of fans and dust collectors may be employed as conditions warrant or dictate and further, an adjustable nozzle may be employed in connection with the opening 14 which nozzle may be arranged as may be desired for effecting a better draught within the chimney.

Having thus described my invention, what I claim as new and desire to secure by Letters Patent is:

1. An arrangement for removing solid particles, particularly dust, from the flue gases in a chimney, comprising a concentrator consisting of a frustum shaped shell along the inside of which is formed a concentrated dust film, said concentrator forming part of the chimney and being provided with a circumferential slit opening at one end of the concentrator shell, said slit being surrounded by a channel connected to a separate dust collector for removing the dust from said dust film, said dust collector being connected to means for sucking out the cleaned gas and forcing the same back again to the concentrator at a point located in front of said slit, seen in the direction of flow of the flue gases through the chimney, said cleaned gas entering tangentially into the concentrator shell to set the flue gases in rotation for obtaining said concentrated dust film.

2. An arrangement for removing solid particles, particularly dust, from the flue gases in a chimney, comprising a concentrator consisting of a frustum shaped shell along the inside of which is formed a concentrated dust film, said concen-

trator forming part of the chimney and being provided with a circumferential slit opening at one end of the concentrator shell, said slit being surrounded by a channel connected to a separate dust collector for removing the dust from said dust film, said dust collector being connected to means for sucking out the cleaned gas and forcing the same back again to the concentrator at a point located in front of said slit, seen in the direction of flow of the flue gases through the chimney, said cleaned gas entering tangentially into the concentrator shell to set the flue gases in rotation for obtaining said concentrated dust film, said inlet opening for the cleaned gas being combined with nozzles and provided variable as to direction in such a manner that said gas is crossing the gas flow through the chimney on a variable distance from the axis of the chimney for regulating the draught.

3. An arrangement for removing solid particles, particularly dust, from the flue gases in a chimney, comprising a concentrator consisting of a frustum shaped shell along the inside of which is formed a concentrated dust film, said concentrator forming part of the chimney and being provided with a circumferential slit opening at one end of the concentrator shell, said slit being surrounded by a channel connected to a separate dust collector for removing the dust from said dust film, said dust collector being connected to means for sucking out the cleaned gas and forcing the same back again to the concentrator at a point located in front of said slit, seen in the direction of flow of the flue gases through the

chimney, said cleaned gas entering tangentially into the concentrator shell to set the flue gases in rotation for obtaining said concentrated dust film, a centrally arranged streamline shaped guiding body having its largest diameter located about at the inlet of said cleaned gas and extending to about said slit to force the gas towards the inside of said concentrator shell.

4. An arrangement for removing solid particles, particularly dust, from the flue gases in a chimney, comprising a concentrator consisting of a frustum shaped shell along the inside of which is formed a concentrated dust film, said concentrator forming part of the chimney and being provided with a circumferential slit opening at one end of the concentrator shell, said slit being surrounded by a channel connected to a separate dust collector for removing the dust from said dust film, said dust collector being connected to means for sucking out the cleaned gas and forcing the same back again to the concentrator at a point located in front of said slit, seen in the direction of flow of the flue gases through the chimney, said cleaned gas entering tangentially into the concentrator shell to set the flue gases in rotation for obtaining said concentrated dust film, a centrally arranged streamline shaped guiding body having its largest diameter located about at the inlet of said cleaned gas and extending to about said slit to force the gas towards the inside of said concentrator shell, said guiding body being axially adjustable.

TOM CONRAD BIETH.
